UNITED STATES PATENT OFFICE.

VALÈRE ALFRED FYNNE, OF LONDON, ENGLAND.

ALTERNATING-CURRENT MOTOR.

962,334.

Specification of Letters Patent. Patented June 21, 1910.

Application filed July 3, 1909. Serial No. 505,778.

To all whom it may concern:

Be it known that I, VALÈRE ALFRED FYNNE, a subject of the King of England, residing at London, England, have invented a certain new and useful Alternating-Current Motor, of which the following is such a full, clear, and exact description as will enable any one skilled in the art to which it appertains to make and use the same, reference being had 10 to the accompanying drawings, forming part of this specification.

My invention relates to means for starting and operating single phase induction motors in which the induced winding responsible 15 for the operation of the motor is permanently closed on itself independently of any commutator. It is known that motors of this type have distinct mechanical advantages and good operating characteristics but 20 are difficult to start with a powerful torque and with a small current or in other words with a large torque per ampere.

One object of my invention is to provide such means for starting said motors with a 25 large torque per ampere as will not make it necessary to dimension or dispose the secondary working winding permanently closed on itself with any other objects in view but those of highest effectiveness and efficiency 30 under normal running conditions.

Other objects of my invention are to avoid the use of all automatic short-circuiting devices inside the rotor, to provide means for compensating such machines and to generally 35 improve their characteristic properties both at starting and under normal working conditions.

I achieve my objects by providing my motor with a rotor having a permanently 40 short-circuited winding extending over all the rotor laminations and a plurality of commuted windings longitudinally displaced and extending over a part only of the rotor laminations, by conveying a working current 45 to each commuted winding and neutralizing the effects of such currents on the short-circuited winding, by producing a motor flux threading each commuted winding and adapted to produce a starting torque with 50 the ampere turns due to the corresponding working current while neutralizing the effects of said motor fluxes on the short-circuited winding and by inducing currents in

the short-circuited winding either at the moment of starting or after the motor has 55 reached a sufficient speed, thus limiting the speed of the machine and converting same into a self-excited shunt induction motor and finally by impressing on at least one of the commuted windings, preferably after 60 the motor has reached a sufficient speed, an E. M. F. of suitable phase for improving the power factor *i. e.* compensating the motor. Thus in my preferred form of motor I provide a permanently short circuited 65 working winding on the induced or secondary member together with two commuted windings on that member and so wind the inducing or primary member that in one connection or combination of its windings 70 the secondary working winding permanently closed on itself will not carry any currents, whereas in another connection or combination of the windings on the inducing member the secondary working winding permanently closed on itself will have currents induced in it which will close in that winding without the help of a commutator. The first connections are used at starting, the second are used in normal operation. I 75 further so connect or combine the windings disposed on the primary member that the motor may start as a series induction, as a series or a shunt conduction motor. In normal operation one or more of the commuted 80 windings may in some modifications, also carry working currents thus contributing to the useful torque.

In all induction motors there is a transformer flux which conveys energy from the 85 inducing to the induced member, and a motor flux which produces torque with the current induced in the secondary. In conduction motors there is sometimes a flux due to the working current in the armature and 90 there is always a motor flux. I preferably dispose my windings in such a manner that neither of these fluxes will produce any currents in the permanently short-circuited secondary working winding at starting and before the primary connections have been altered from the starting to the running connections. I may make the necessary change in the connections automatically or by hand. If an automatic, for instance a centrifugal, 95 device is used it can be placed outside the 100 105

motor; it can therefore always be made easily accessible, can be kept in good condition and can be quickly repaired or replaced. When the machine has reached a sufficient speed I can make use of one or more of the commuted windings for the purpose of compensating, *i. e.* improving the power factor of the machine. By suitably interconnecting the commuted windings I can cause a working current to flow through these windings independently of the commutator, thus relieving the latter and obviating all danger of sparking.

In describing some ways of carrying my invention into practice I will refer to the accompanying diagrammatic drawings of two-pole motors where—

Figure 1 shows a motor in which the two commuted windings are interconnected, which is capable of being compensated and is arranged to start as a separately excited series induction machine with the motor field winding disposed on the inducing member. Fig. 2 indicates the mechanical disposition of the motor parts for the machine shown in Fig. 1. Fig. 3 is a motor capable of being compensated and arranged to start as a separately excited series induction motor with the motor field winding disposed on the induced member. Fig. 4 is a motor capable of being compensated by means of a transformer independent of the motor and arranged to start as a self-excited series induction motor in which the motor field winding is disposed on the induced member. Fig. 5 is a motor capable of being compensated and arranged to start mainly as a neutralized series conduction motor. Fig. 6 is a motor capable of being compensated and arranged to start as a shunt conduction motor.

Fig. 1 shows a motor with two longitudinally displaced primary or stator windings 7 and 8 disposed along parallel axes, arranged to be connected in parallel and to be fed from the mains 1, 2 by way of a transformer having a primary 3 and a secondary 4. The movable contact 5 on the latter controls the magnitude of the E. M. F. impressed on the circuit containing 7, whereas 6 controls the magnitude of the E. M. F. impressed on the circuit containing 8. An automatic switch 9, here shown as being of the centrifugal type, is adapted to be geared to the motor shaft for instance by means of the pulley 10. When the motor is at rest the contact levers 11 and 12 of 9, which are insulated from the body of 9, are in the position shown; after the motor has reached a sufficient speed these levers leave contacts 15, 20 and 17, 14 and bridge the contacts 13, 19 and 18, 16. It is best to so design 9 as to cause these levers to "snap" from the starting to the running position. The sec-

ondary short-circuited working winding is 65 shown, mainly for convenience and clearness of illustration as consisting of two longitudinally displaced and permanently interconnected windings 24, 25. They are shown as being interconnected at four points, but they 70 can be interconnected at any desired number of points, the more the better. In this case 24 and 25 are so interconnected that the E. M. F.'s induced in them by 7 and 8 respectively, oppose each other when 7 and 8 magnetize 75 in opposite directions and vice versa. The rotor also carries two longitudinally displaced and similarly interconnected commuted windings 34, 35. The first is short-circuited by means of the brushes 36, 37 80 along an axis approximately coinciding with that of 7, the second is short-circuited by the brushes 40, 41 along an axis approximately coinciding with that of 8.

Each commuted winding carries exciting 85 brushes 38, 39 and 42, 43; these exciting brushes are displaced by about $180/n$ degrees with respect to the corresponding short-circuited brushes or with respect to the axes of 7 and 8 respectively. The letter n stands 90 throughout for the number of poles of the motor. The exciting brushes 38, 39 can be connected to the compensating winding 54 by means of the reversing switch 76. The exciting brushes 42, 43 can be connected to 95 the compensating winding 55 by means of 77. The direction of the compensating E. M. F. is controlled by 76, 77, these switches being closed in the one or the other direction 100 according to the direction of rotation and after the motor has reached a sufficient speed. Switch 74 controls the direction of the current through the motor field windings 66, 67 disposed on the inducing member. This switch, therefore, controls the 105 direction of rotation of the motor. Switch 71 is adapted to cut the stator field windings 66, 67 out of circuit. At starting all switches are in the positions shown. With reference to the short-circuited winding 24, 110 25, the inducing winding 8 magnetizes in a direction opposite to that of the magnetization due to 7 and the movable contacts 5 and 6, if such are used, are preferably so adjusted that the E. M. F.'s induced in 24 115 and 34 are of equal magnitude to those induced in 25 and 35 respectively. At starting the primary circuit is as follows: from point 52 of 4 to switch 74 through 66, 67 in one or the other direction, out through 71 and 120 74 to point 51 from there through 7 and 5 back to 4 and also from 51 through 17, 11, 14 to 8 and through 15, 12, 20 and 6 back to 4.

Since the magnetizations due to 7 and 8 125 are of opposite direction with respect to 24, 25 and since the E. M. F.'s they induce in 24, 25 and 34, 35 respectively are of equal

magnitude then no current will flow by way of the interconnections between 24 and 25, *i. e.* there will be no current from 28 to 29, 26 to 27, 56 to 57 and so on. The effect of 5 the transformer fluxes on the short-circuited working winding is thus eliminated.

The E. M. F.'s induced in the commuted windings 34, 35 will, however, determine a local current in each of them. These local 10 currents will close by way of the short-circuited brushes 36, 37 and 40, 41 respectively. The current in 34 will be of opposite direction to that in 35 and in order that these 15 two windings shall give torques in the same direction the primary current conducted through 66 for the purpose of generating a motor field adapted to interact with the current induced in 34 must be conducted through 67 in a direction opposed to that in which 20 it is conducted through 66. This is clearly shown in Fig. 1. This motor starts as a separately excited series induction motor, the longitudinally displaced stator windings 66, 67 doing duty as motor field windings. 25 Since the fluxes due to 66 and 67 are of opposite direction with respect to 24, 25 their effect on the short-circuited working winding 24, 25 will be *nil* provided the magnitude 30 of these fluxes is approximately the same, nor will these fluxes cause any currents to flow in the connections between 34 and 35. Since these fluxes are due to the same current it is only necessary that the number of turns in 66, 67 and the relative 35 space position of 66 to 24, 34 and of 67 to 25, 35 as well as the relative brush positions be sensibly the same in order that this desired condition may be practically fulfilled. It is seen that the short-circuited 40 working winding 24, 25 is quite idle at starting.

As the motor gathers speed the E. M. F. impressed on 8 may, if desired, be gradually diminished down to zero, when 8 will be 45 short-circuited. After that the E. M. F. impressed on 8 may be gradually increased in the opposite direction. In most cases it will be quite sufficient to simply reverse the current through 8 after the motor has 50 reached a sufficiently high speed. In Fig. 1 this is achieved by means of the automatic switch 9. As soon as 8 has been reversed then the combined windings 24, 25 and 34, 35 act just like the ordinary short-circuited 55 secondaries of a self-excited single-phase shunt induction motor of ordinary construction, both these combined windings becoming working windings. The brushes could now all be lifted off the commutators but I 60 prefer to leave all the brushes on the commutator and to close the circuit of the exciting brushes so as to include a compensating E. M. F. in the exciting circuits of either 34 or 35 or of both, thus making use of 34,

35 for compensating purposes as well as for 65 carrying part of the load current. This compensation is achieved in Fig. 1 by closing switches 76 and 77 in the proper direction. It is preferred, after the motor has reached a sufficiently high speed, to cut 66 70 and 67 out of circuit by means of 71. The windings 7 and 8 are shown connected in parallel but it is obvious that they can also be connected in series and if it were not for the fact that the current through one of 75 them must in this case be capable of being reversed they could be replaced by a single winding. A modified construction embodying this idea is shown in Fig. 6.

In order to provide for an easy accommodation of the longitudinally displaced stator and rotor windings the motor laminations can be split up into two groups in the manner indicated in Fig. 2. The two groups of stator laminations are shown at 44 and 45; 80 the two longitudinally displaced stator windings at 7 and 8; the two compensating windings at 54, 55; the field windings at 66, 67. The two groups of rotor laminations are shown at 46, 47. They are mounted 85 on the same shaft and are spaced to correspond to 44 and 45. The two longitudinally displaced commuted windings are shown at 34, 35; their respective commutators at 48, 49 and their interconnections are 90 indicated at 75. In Fig. 1 the working winding 24, 25 permanently closed on itself independently of a commutator has been shown for the sake of convenience as consisting of two separate longitudinally displaced windings interconnected at 4 points. 95 As has been already pointed out 24, 25 may be interconnected at any number of points and it will be clear that these two interconnected windings are electrically equivalent 100 to a single winding, for instance to a squirrel cage such as shown in Fig. 2 and wound straight through both groups of the rotor laminations. This squirrel cage has been designated by the two numerals 24, 25 105 in Fig. 2 so as to draw attention to the fact that it is the equivalent of the two interconnected windings 21, 25 of Fig. 1. In practice it will generally be more advantageous 110 to make use of a squirrel cage construction for the working winding permanently closed on itself. It is immaterial whether the two groups of laminations 44, 45 are inclosed within the same or within separate frames. It is, however, necessary 115 that the two groups of rotor laminations be rigidly coupled and that the part of the short circuited working winding disposed on one group of rotor laminations be electrically connected at a plurality of points to 120 that part of this same winding which is disposed on the other group of rotor laminations. The stator windings 7, 8 need not 125

be disposed along parallel axes. The windings disposed on 44, 46 have been shown in Figs. 1 and 2 as 2 pole windings, those disposed on 45, 46 have also been shown as 2 pole windings, but this is by no means necessary although it is the preferred arrangement. The number of poles of the windings disposed on one group of stator and rotor laminations may differ to any desired extent 10 from that of the windings disposed on another group of such laminations.

In Fig. 3 the two longitudinally displaced stator windings 7, 8 are directly connected to the mains 1, 2, the reversing switch 53 is 15 arranged to control the direction of the current through 8. The inducing windings 7 and 8 magnetize in opposite directions at starting but the current through 8 is reversed after the motor has reached a sufficient speed. Accordingly the rotor working 20 winding permanently closed on itself is so arranged that the E. M. F.'s induced therein oppose each other when 7 and 8 magnetize in opposite directions and are in the same 25 direction when 7 and 8 magnetize in the same direction. This is diagrammatically indicated in Fig. 3 by connecting point 28 to 29, point 26 to 27, point 32 to 33 and point 30 to 31. The motor field is produced by 30 connecting the commuted windings 34, 35 in series relation with the inducing stator windings. This is achieved in Fig. 3 by connecting point 51 to brush 38, brush 39 to brush 43 and brush 42 to the main 2. The 35 line current is thus taken through the rotor along an axis displaced by about $180/n$ degrees with respect to the axes of 7 and 8. Since the current induced in 34 at starting is of opposite direction to that induced in 40 35 then the exciting current must be taken in opposite directions through 34 and 35 in order to secure torques in the same direction. The commuted windings 34, 35 are not 45 interconnected in this case, but they are nevertheless active at starting and in normal operation. All the currents flowing in these windings now close by way of the commutator only even in normal operation. When 50 34, 35 are not interconnected then a common source of compensating E. M. F. can be made use of. In this case the exciting brushes on both windings are connected to part 23 of winding 7 when switches 21 and 22 are closed and this part 23 of 7 then acts 55 as compensating winding. Switches 21, 22 are preferably closed after the motor has reached a sufficient speed and the current through 8 has been reversed.

In Fig. 4 the windings 7, 8 are arranged to 60 magnetize in the same direction at starting. The commuted windings 34, 35 are not interconnected although they can be interconnected if desired. The interconnections of 24, 25 are also altered. Thus point 28 is

connected to point 33 instead of 29 and so 65 on. If 34 and 35 are to be interconnected then point 56 should be connected to 61 and so on. The starting is accomplished by displacing the short-circuited brushes 36, 37 from the axis of 7 and the short-circuited 70 brushes 40, 41 from the axis of 8. Since the torques due to 34 and 35 are to add these displacements should be in the same direction, irrespective of the relative direction of the magnetization due to 7 and 8 respectively, and the degree of displacement should be such in each case that the motor field due to 35 equals the motor field due to 34, thus 75 eliminating the action of those motor fields on the short-circuited working winding 24, 25 at starting. After the motor has reached a sufficient speed the current through 8 is reversed and if phase compensation is desired then switches 21, 22 are closed thus 80 impressing compensating E. M. F.'s on the exciting brushes 38, 39 and 42, 43. These E. M. F.'s are here derived from a shunt transformer, the primary 68 of which is connected across the mains 1, 2. This transformer 85 has two independent and regulatable secondaries 78, 79. If 34, 35 are not interconnected then one secondary is sufficient. The short circuited brushes may be moved so as to coincide with the axes of 7 and 8 after the 90 motor is up to speed. The direction of rotation can be reversed by moving the short-circuited brushes beyond the axes of 7 and 8. If the short circuited working winding 24, 25 were for instance of the squirrel cage 95 type then one and the same bar would have 100 to pass the two groups of rotor laminations through slots displaced by about $360/n$ degrees in order to correspond to the interconnections between 24 and 25 which are shown 105 in Fig. 4.

The motor shown in Fig. 5 carries two inducing windings 7 and 8 connected in parallel. The two parts 24 and 25 of the short-circuited working winding are so interconnected 110 that this winding will be responsive to induction effects due to 7 and 8. In practice a squirrel cage such as shown in Fig. 2 would be used instead of the interconnected windings 24, 25. The actual starting circuit consists of the neutralizing windings 115 99, 98, the commuted windings 34, 35 and the motor field windings 66, 67. All the elements of this starting circuit are connected in series, the commuted windings being included by way of the brushes 36, 37 and 120 40, 41 respectively. At starting switch 74 stands on points 101, 103 and switch 100 can be left open. The machine starts as a neutralized series conduction motor and the torque and speed may be varied by adjusting the movable contact 6 on the secondary 125 4 of the transformer with the primary 3 feeding the motor from mains 1, 2. When

a sufficient speed has been reached switch 100 is closed thus bringing the short-circuited rotor working winding into play and converting the machine into a self-excited shunt induction motor. The starting circuit may now simply be opened thus rendering the commuted windings idle or these may be made use of to compensate the machine. One way of achieving this is shown in Fig. 5 and consists in moving 74 on to points 102 and 104. The motor field windings 66, 67 now act as compensating windings, the compensating E. M. F.'s being induced therein by 7 and 8. The whole or part only of the motor field windings may be used for compensating purposes. Since the currents flowing through 34 and 35 at starting flow in relatively opposite directions than the fluxes they would set up will not induce currents in 24, 25 and the neutralizing windings 99, 98 can be omitted if desired. Switch 100 can be closed at starting and although this will reduce the torque per ampere yet the fluxes due to 7 and 8 will not otherwise interfere with the starting operation and will prevent the motor from racing. The two windings 7 and 8 can of course be replaced by a single one embracing both groups of stator laminations.

In Fig. 6 the stator carries three windings. One of these embraces both groups of stator laminations and is shown at 97. It takes the place of the two windings 7 and 8 of Fig. 5 whether the latter be connected in series or in parallel. The windings 24, 25 are so interconnected as to form a short-circuited winding responsive to inductive effects due to 97. The stator windings 117 and 118 are adapted to produce fluxes which link with 34 and 35 respectively and are conductively connected to these commuted windings by way of the brushes 36, 37 and 40, 41 respectively. At starting switch 119 stands on points 115, 116 thus connecting 117 and 118 in parallel and to the supply. The motor starts as a shunt conduction machine owing to the interaction of the fluxes due to 117 and 118 threading 34 and 35 and the ampere turns in 34 and 35 due to the currents derived from 117 and 118 and conducted through 34 and 35 respectively by way of the brushes. The starting torque can be regulated at 120 and 121. When a sufficient speed has been reached switch 119 is thrown on to point 114 whereby 117, 118 are disconnected from the supply and 97 is connected to the mains 1, 2. The short-circuited working windings 24, 25 now comes into play. The flux due to 97 also induces E. M. F.'s in 117 and 118. These E. M. F.'s are made use of for compensating the machine and no further change of connections is required to achieve this purpose for the commuted windings are already connected

to 117 and 118 by way of the brushes 36, 37 65 and 40, 41. The magnitude of the compensating E. M. F.'s can be adjusted at 120 and 121. If 97 is connected to the supply at starting then the motor will never exceed its normal speed but the torque per ampere at 70 starting will be somewhat reduced particularly if the full line voltage is impressed on 97 from the very first.

Having fully described my invention, what I claim as new and desire to secure by Letters Patent of the United States is:

1. In an alternating current motor, the combination with a stator, of a laminated rotor provided with a permanently short-circuited winding and two commuted windings, said short-circuited winding extending over all the rotor laminations and each of said commuted windings extending over a part only of the rotor laminations. 80

2. In an alternating current motor, the combination with a stator provided with a plurality of windings, of a laminated rotor provided with a permanently short-circuited winding and two commuted windings, said short-circuited winding extending over all 90. the rotor laminations and each of said commuted windings extending over a part only of the rotor laminations.

3. In an alternating current motor, the combination with a stator provided with a plurality of windings, of a rotor containing two longitudinally displaced groups of laminations and provided with a permanently short-circuited winding and two commuted windings, said short-circuited winding extending over both groups of rotor laminations and each of said commuted windings extending over only one group of rotor laminations. 100

4. In an alternating current motor, a stator containing two longitudinally displaced groups of laminations, means for producing a main flux through each group of laminations, a laminated rotor provided with a permanently short-circuited winding 110 and two commuted windings, said short-circuited winding extending over all the rotor laminations and each of said commuted windings extending over a part only of the rotor laminations. 115

5. In an alternating current motor, a stator containing two longitudinally displaced groups of laminations, each group being provided with a main winding, a laminated rotor provided with a permanently short-circuited winding and two commuted windings, said short-circuited winding extending over all the rotor laminations and each of said commuted windings extending over a part only of the rotor laminations. 120

6. In an alternating current motor, a stator containing two longitudinally displaced groups of laminations, means for

producing a main flux through each group of laminations, two auxiliary windings, one of which is coaxially disposed with reference to the main flux through one group of 5 laminations, a laminated rotor provided with a permanently short-circuited winding and two commuted windings, said short-circuited winding extending over all the rotor laminations and each of said commuted windings extending over a part only 10 of the rotor laminations.

7. In an alternating current motor, a stator containing two longitudinally displaced groups of laminations, means for 15 producing a main flux through each group of laminations, an auxiliary winding coaxially disposed with reference to the main flux through one group of laminations, a laminated rotor provided with a permanently short-circuited winding and two commuted windings, said short-circuited winding extending over all the rotor laminations and each of said commuted windings extending over a part only 20 of the rotor laminations.

8. In an alternating current motor, a stator containing two longitudinally displaced groups of laminations, means for 30 producing a main flux through each group of laminations, two auxiliary windings, one of which is coaxially disposed with reference to the main flux through one group of laminations, a laminated rotor provided with a permanently short-circuited winding and two commuted windings, said short-circuited winding extending over all the rotor laminations and each of said commuted windings extending over a part only 35 of the rotor laminations, and separate means for directing the flow of current in each of the commuted windings.

9. In an alternating current motor, a stator containing two longitudinally displaced groups of laminations, means for 45 producing a main flux through each group of laminations, an auxiliary winding coaxially disposed with reference to the main flux through one group of laminations, a laminated rotor provided with a permanently short-circuited winding and two commuted windings, said short-circuited winding extending over all the rotor laminations and each of said commuted windings extending over a part only 50 of the rotor laminations, and separate means for directing the flow of current in each of the commuted windings.

10. In an alternating current motor, a stator containing two longitudinally displaced groups of laminations, means for 60 producing a main flux through each group of laminations, a laminated rotor provided with a permanently short-circuited winding and two commuted windings, said short-circuited winding extending over all the rotor laminations and each of said commuted windings extending over a part only 65 of the rotor laminations, and separate means for directing the flow of current in each of the commuted windings.

cuated winding extending over all the rotor laminations and each of said commuted windings extending over a part only of the rotor laminations, and separate means for directing the flow of current in each of the commuted windings.

11. In an alternating current motor, the combination with a laminated rotor provided with a permanently short-circuited winding and two commuted windings, said short-circuited winding extending over all 70 the rotor laminations and each of said commuted windings extending over a part only of the rotor laminations, of two stator windings longitudinally displaced from each other and adapted to produce magnetic 75 fluxes through the rotor, said magnetic fluxes being of such position and direction at starting that the permanently short-circuited winding will be inoperative.

12. In an alternating current motor, a rotor containing two longitudinally displaced groups of laminations and provided with a permanently short-circuited winding extending over both of said groups and two commuted windings each extending over 85 only one of said groups, and means for producing a transformer flux through each group of rotor laminations and means for producing a motor flux through each group of rotor laminations at starting.

13. In an alternating current motor, a rotor containing two longitudinally displaced groups of laminations and provided with a permanently short-circuited winding extending over both of said groups and two 95 commuted windings each extending over only one of said groups, said commuted windings being interconnected at a plurality of points, and means for producing a transformer flux through each group of rotor laminations and means for producing a motor flux through each group of rotor laminations at starting.

14. In an alternating current motor, a stator containing two longitudinally displaced groups of laminations, means for producing a main flux through each group of laminations, a rotor containing two longitudinally displaced groups of laminations and provided with a permanently short-circuited winding and two commuted windings, said short-circuited winding extending over both groups of laminations and each 110 of said commuted windings extending over only one group of laminations.

15. In an alternating current motor, a stator containing two longitudinally displaced groups of laminations, means for producing a main flux through each group of laminations, two auxiliary windings, one of 115 which is coaxially disposed with reference to the main flux through one group of laminations, a rotor containing two longitudi-

nally displaced groups of laminations and provided with a permanently short-circuited winding and two commuted windings, said short-circuited winding extending over both 5 groups of laminations and each of said commuted windings extending over only one group of laminations.

16. In an alternating current motor, a stator containing two longitudinally displaced groups of laminations, means for producing a main flux through each group of laminations, an auxiliary winding coaxially disposed with reference to the main flux through one group of laminations, a rotor 10 containing two longitudinally displaced groups of laminations, and provided with a permanently short-circuited winding and two commuted windings, said short-circuited winding extending over both groups of laminations and each of said commuted windings extending over only one group of laminations.

17. In an alternating current motor, a stator containing two longitudinally displaced groups of laminations, each group being provided with a main winding, a rotor containing two longitudinally displaced groups of laminations and provided with a permanently short-circuited winding and two commuted windings, said short-circuited winding extending over both groups of laminations and each of said commuted windings extending over one group of laminations, and brushes for conductively conveying a current to each commuted winding along an axis displaced from the axis of the corresponding main stator winding.

18. In an alternating current motor, a stator containing two longitudinally displaced groups of laminations, each group being provided with a main winding, two auxiliary windings, one of which is coaxially disposed with reference to one of said main windings, a rotor containing two longitudinally displaced groups of laminations and provided with a permanently short-circuited winding and two commuted windings, said short-circuited winding extending over both groups of laminations and each of 50 said commuted windings extending over only one group of laminations, and brushes for conductively conveying a current to each commuted winding along an axis displaced from the axis of the corresponding main stator winding.

19. In an alternating current motor, a stator containing two longitudinally displaced groups of laminations, each group being provided with a main winding and two auxiliary windings, one of which is coaxially disposed with reference to said main winding, a rotor containing two longitudinally displaced groups of laminations and provided with a permanently short-circuited

winding and two commuted windings, said 65 short-circuited winding extending over both groups of laminations and each of said commuted windings extending over only one group of laminations, brushes for conductively conveying a current to each commuted winding along an axis displaced by approximately $180/n$ degrees from the axis of the corresponding main stator winding, and brushes for short-circuiting each commuted winding along another axis.

20. In an alternating current motor, a stator containing two longitudinally displaced groups of laminations, each group being provided with a main winding, a rotor containing two longitudinally displaced groups of laminations and provided with a permanently short-circuited winding extending over both groups of laminations and each of said commuted windings extending over only one group of laminations, 80 brushes for conductively conveying a current to each commuted winding along an axis displaced by approximately $180/n$ degrees from the axis of the corresponding stator winding, and brushes for short-circuiting each commuted winding along another axis.

21. In an alternating current motor, a stator containing two longitudinally displaced groups of laminations, each group being provided with a main winding, a rotor 95 containing two longitudinally displaced groups of laminations and provided with a permanently short-circuited winding and two commuted windings, said short-circuited winding extending over both groups of laminations and each of said commuted windings extending over only one group of laminations, and means for reversing the current through one of the main stator windings.

22. In an alternating current motor, a 105 stator containing two longitudinally displaced groups of laminations, each group being provided with a main winding and two auxiliary windings, one of which is coaxially disposed with reference to said main winding, a rotor containing two longitudinally spaced groups of laminations and provided with a permanently short-circuited winding and two commuted windings, said short-circuited winding extending over both 110 groups of laminations, brushes for conductively conveying a current to each commuted winding along an axis displaced by approximately $180/n$ degrees from the axis of the corresponding main stator winding, brushes for short-circuiting each commuted winding along another axis, and automatic means for reversing the current through one of the main stator windings.

23. In an alternating current motor, the 125 combination with a stator, of a laminated rotor provided with a permanently short-circuited winding and two commuted wind-

ings, said short-circuited winding extending over all the rotor laminations and each of said commuted windings extending over a part only of the rotor laminations and means 5 for impressing a compensating E. M. F. on at least one of the commuted windings.

24. In an alternating current motor, a rotor containing two longitudinally displaced groups of laminations and provided 10 with a permanently short-circuited winding extending over both of said groups and two commuted windings each extending over only one of said groups, means for produc-

ing a transformer flux through each group of rotor laminations and means for producing 15 a motor flux through each group of rotor laminations at starting, and means for impressing a compensating E. M. F. on at least one of the commuted windings.

In testimony whereof I have hereunto set 20 my hand and affixed my seal in the presence of the two subscribing witnesses.

VALÈRE ALFRED FYNN. [L. S.]
